G. P. EDMONDS

ELECTRICAL CONDUCTOR PROTECTING MEANS

Filed Nov. 2, 1925

Fig. 1

UNITED STATES PATENT OFFICE.

GEORGE P. EDMONDS, OF CHICAGO, ILLINOIS, ASSIGNOR TO G. & W. ELECTRIC SPECIALTY COMPANY, OF CHICAGO, ILLINOIS, A CORPORATION OF ILLINOIS.

ELECTRICAL-CONDUCTOR-PROTECTING MEANS.

Application filed November 2, 1925. Serial No. 66,165.

This invention relates to electrical conductor protecting means.

One object of the invention is to provide simple and efficient enclosure protecting means for electrical conductors arranged to prevent the passage of moisture along the threads of the threaded members and into the enclosure to protect insulation of the electrical conductors from rupturing.

10 Another object is to provide a moisture-proof cap arrangement for a casing or bushing in which an insulated electrical conductor is placed to maintain the dielectric strength of such insulation.

15 These and other objects are accomplished by means of the arrangement disclosed on the accompanying sheet of drawings, in which—

20 Figure 1 is a front elevation, parts being in section, of a non-disconnecting pothead embodying my invention; and,

Figure 2 is a sectional view taken in the plane of line 2—2 of Figure 1.

25 While I have disclosed my invention particularly in connection with a pothead, it is to be understood that the invention is to be considered broadly with respect to any casing for enclosure for insulated electrical conductors.

30 In the particular arrangement shown, it will be noted that the invention is illustrated in connection with a pothead including a porcelain bushing 10, to the lower part of which a metal threaded ring 11 is secured by cement 12 or the like, an insulating containing cap 13 being screwed onto the ring 11. Said cap is provided with a plug 14 which may be removed for filling the cap and bushing with liquid insulating material. The electrical ca-

35 ble or conductor 15 enters the tapered end of the cap 13 and extends upwardly through the bushing 10 and is electrically connected to the lower end of an electrical connector 16 having projections 17 which are anchored to a brass anchor ring 18 suitably secured in the upper part of the bushing 10 by cement 19 or the like. As is customary, adjacent the end of the conductor which is electrically connected to the connector 16 the wrapped insulation 20 around the conductor is removed

40 and the strands 21 of the cable untwisted so that they are expanded for the purpose of impregnating same for preventing any moisture which may enter the top of the bushing

from leaking down through the strands and 55 into the insulation surrounding the conductor. As is well understood, moisture in insulation weakens the dielectric strength thereof, resulting in the formation of arcs and possible destruction of the insulation, ca- 60 ble and the entire device.

To prevent the admission of moisture through the top of the casing or porcelain 10, a moisture-proof covering has been provided. This covering includes a skirted nut 22, the 65 skirt 23 of which passes down over the top of the porcelain 10, said hooded nut having a threaded body portion 23' and a threaded sleeve portion 24 which are screwed onto the threaded portion 25 of the electrical connector for clamping the connector within the porcelain and for securing the hooded nut in a protecting position over the top of the porcelain. The real function of the sleeve 24 will be emphasized later. The hooded nut 75 22 is metal to form an electrical connection between it and the connector 16. Mounted over the body portion 23' of the nut 22 and embracing the sleeve 24 thereof is a cable lug 26, and threaded onto the upper end 25 of the 80 connector 16 is a cap nut 27 which presses down against the cable lug 26 and presses the latter into close electrical contact with the hooded nut 22.

It will be noted that the lower surface of 85 the cable lug 26 engages the hooded nut 22 in the plane of line 28 and that the lower surface of the cap nut 27 engages the upper surface of the cable lug in the plane of line 29. It will also be noted that the sleeve 24 90 of the hooded nut 22 extends upwardly a considerable distance beyond the interengaging surfaces at lines 28 and 29 of the cable lug 26, hooded nut 22 and cap nut 27. It is seen, therefore, that if any moisture should 95 seep between the connecting surfaces at 28 and 29, such moisture, because of the sleeve 24, could not pass into engagement with the threaded portion 25 of the connector, and accordingly, could not pass down along the 100 conductor and into the insulation 20. Therefore, the insulation 20 is thoroughly protected by the arrangement shown against being moistened and thereby prevented from having its dielectric strength weakened. In 105 this way, the dielectric strength of the insulation around the electrical conductor is maintained, arcing is prevented and the

cable and the entire device are protected against destruction.

I claim:

1. In combination, a casing for protecting an electrical conductor, an electrical conductor therein, an electrical connector electrically connected to said conductor, a metal skirted nut closing and covering one end of said casing and screwed onto said connector, said skirted nut having a sleeve extending along a threaded portion of said connector, a cable lug mounted over and embracing said sleeve of said nut, and a cap nut screwed onto said connector and extending over said sleeve, said sleeve extending up beyond the interengaging portions of said cable lug, skirted nut and cap nut whereby moisture is prevented from reaching the threaded portions
- 10
- 15

of said members and is thereby prevented from reaching the enclosed conductor.

20

2. In combination, a casing for protecting an electrical conductor, an electrical conductor therein, a threaded electrical connector electrically connected thereto, and a closure for one end of said casing electrically connected to said connector and comprising a skirted nut, a cable lug and a cap nut, said skirted nut having a sleeve extending beyond interengaging portions of said cable lug, skirted nut and cap nut, whereby moisture is prevented from reaching the enclosed conductor.

25

Signed at Chicago, Illinois, this 29 day of October, 1925.

GEORGE P. EDMONDS.
